UNITED STATES PATENT OFFICE.

FREDERICK WESTERBECK, OF ST. LOUIS, MISSOURI.

SHEET-METAL CAN.

979,813.

Specification of Letters Patent. Patented Dec. 27, 1910.

Application filed June 16, 1909. Serial No. 502,413.

To all whom it may concern:

Be it known that I, FREDERICK WESTERBECK, a citizen of the United States of America, residing in the city of St. Louis and State of Missouri, have invented certain new and useful Improvements in Sheet-Metal Cans, of which the following is a full, clear, and exact description, reference being had to the accompanying drawings, forming part of this specification.

My invention relates to an improvement in sheet metal cans of the description commonly known as "friction top" cans, and it has for its object the production of a can of this description whereby an efficient seal between the cover and the top of the can may be effected, and also whereby the cover of the can may be efficiently locked to the top of the can body, thereby preventing all liability of leakage from the can, and the separation of the cover from the can body until force is properly applied thereto for the separation of these parts.

Figure I is in part an elevation and in part a vertical section of the upper portion of the body of my can; the cover being omitted. Fig. II is in part an elevation and in part a vertical section of the upper portion of my can with the cover applied to the can body. Fig. III is an enlarged vertical section through fragments of the top of the can body and the cover fitted thereto.

In the accompanying drawings: 1 designates the main part of the body of my can, and 2 the top part of said body secured to said main part. The top part is provided with an annular neck 3 having an outwardly jutting vertical portion 4, above which is an outwardly flaring flange 5 having a flat outer face, the flange being bent inwardly and downwardly at its upper end to furnish an annular lip 6 that occupies a position above the flange and is separated therefrom to furnish a pocket between the body flange and its lip.

7 is a flexible annular outwardly flaring flat packing strip or band that rests upon the body of the flange 5 and the upper edge of which is permanently confined between the body of the flange and its annular lip 6. This packing strip, which may be of any suitable material, is preferably made of a material that will expand when moistened, whereby the thickness of the packing strip is increased when subjected to moisture. The packing strip rests initially, or when

put in place, in the neck of the can body so that its lower edge extends beyond the bottom of the flange 5 within the neck of the can body, and is adapted to be pressed outwardly against the jutting vertical portion 4 of the can body neck under pressure exerted thereagainst by the can cover upon its entrance into said neck. While I have stated that the packing strip is preferably of an expanding material, I do not wish to limit myself to the use of such material in making the packing strip, as it may be made of rubber or other suitable material that is not subject to expanding due to the subject of it to moisture.

The cover of my can comprises a bottom or horizontal portion 8, a vertical annular member 9 extending upwardly from said bottom portion, an outturned rim 10 at the top of the vertical member, and a down-turned annular flange 11 carried by the bottom, and provided at its lower edge with a bead 12 within which is a wire ring 13. In applying the cover of my can to the neck of the can body, said cover is introduced into the can body neck so that its vertical member 9 will press against the packing strip 7 and carry the lower portion of said strip outwardly against the jutting portion 4 over the annular neck 3 of the can body neck whereby the packing strip becomes tightly clamped or pressed between said jutting portion of the can body neck and the vertical member of the can cover. The vertical member of the can cover is of sufficient depth to provide for its contacting with the portion of the can body neck beneath the point to which the packing strip extends and beneath the jutting portion 4, thereby furnishing frictional contact between the cover and the can body neck. As the can cover is introduced into the can body neck, the bead 12 carried by the flange of the cover rim strikes against the upper end of the flaring flange 5 at the upper end of the neck of the can body, and said bead and flange are sprung outwardly to a sufficient degree to permit the descent of the bead against the flat outer face of said flaring flange. Then, as the cover continues to descend, the flange 11 and its bead spring inwardly and descend on the flat face of the flaring flange until the cover has been completely seated and the bead has reached a position where it will act to lock and restrain the cover from upward movement and hold it firmly.

in position in the neck of the can body. The wire ring 13 serves to reinforce the bead 12 in order that it may properly perform its office.

5 I claim:

1. The combination in a sheet metal can, of a body having a neck provided at its upper end with an inturned and downwardly extending flange providing an annular lip, 10 a flexible annular outwardly flaring flat packing strip held between the body of the neck and said lip, and a cover insertible into said neck to bear against said packing strip.
2. The combination in a sheet metal can, 15 of a body having a neck provided with an outwardly flaring flange having a flat outer face, a flexible annular outwardly flaring flat packing strip located interiorly of said neck and secured thereto at its upper end, 20 and a cover insertible into said neck to bear against the lower portion of said packing strip beneath the flaring flange of the neck, and having at its upper end a rim extending across the flange of said neck and provided

with a downwardly extending flange having 25 a bead arranged for engagement with the flat outer face of the flange of the neck of the can body.

3. The combination in a sheet metal can, 30 of a body having a neck provided with an outwardly flaring flange having a flat outer face, a flexible annular outwardly flaring flat packing strip located interiorly of said neck and secured thereto at its upper end, and a cover insertible into said neck to bear 35 against the lower portion of said packing strip beneath the flaring flange of the neck, and having at its upper end a rim extending across the flange of said neck and provided with a downwardly curved flange terminat- 40 ing at its lower end in a bead for engagement with the flat outer face of the flange of the can body neck.

FREDERICK WESTERBECK.
